UNITED STATES PATENT OFFICE.

ALONZO W. CRAM, OF HAVERHILL, MASSACHUSETTS, ASSIGNOR TO ABBY F. CRAM, OF SAME PLACE.

HOT-AIR FURNACE.

SPECIFICATION forming part of Letters Patent No. 653,927, dated July 17, 1900.

Application filed October 10, 1899. Serial No. 733,143. (No model.)

To all whom it may concern.

Be it known that I, ALONZO W. CRAM, a citizen of the United States, residing at Haverhill, in the county of Essex and State of Massachusetts, have invented new and useful Improvements in Furnaces, of which the following is a specification.

My invention relates to improvements in furnaces, and which is more especially intended to be used as a hot-air furnace, though it may be used as a hot-water furnace or as a steam-generator, as may be desired, without departing from the spirit of my invention.

The primary object of my invention is to provide a furnace having the greatest possible heating-surface, whereby a saving of fuel and labor is effected, and, secondly, to so construct the furnace that it will operate without the aid of the draft of the chimney, which enables me to utilize the escaping products of combustion for heating purposes in the most effective manner.

In the accompanying drawings, Figure 1 is a vertical perspective sectional view of a furnace embodying my invention. Fig. 2 is a top plan view of the same. Fig. 3 is a detached perspective sectional view of one of the sections of which the heating portion of the furnace is composed.

When the furnace is to be used as a hot-air furnace, an outer casing B of any desired form or style will be used for receiving the air which is to be used and then conveyed to the desired point or points of a building. In closed within this outer casing B is the heating portion A of the furnace, which consists of a plurality of radially-arranged sections K, which in cross-section are of a truncated triangular shape, the truncated end of the 40 triangle forming the inner wall of the fire box or chamber A'. Each of these sections K is provided with a vertical partition a, which has its upper end turned horizontally, as shown at b, and the upper ends of these 45 sections K are provided with openings d, communicating with the upper ends of the fire-chamber A', the said openings being divided by the horizontal portion b of the partition a. As shown, this partition does not extend to 50 the bottom of the chambers K for the purpose of forming a passage-way c, and the par-

tition a serves to divide the sections K into the inner E and the outer chambers or flues G, both of which have communication with the interior of the fire chamber or box A', as 55 clearly shown.

The sections K rest upon a horizontal section S, which surrounds the ash-pit M beneath the grate H, and the lower end of each of the sections K is placed in communication 60 with the horizontal section S through the medium of the vertical pipes O.

One of the sections K is provided with an outwardly-projecting pipe X, and the section S is provided with an outwardly-projecting 65 pipe X", through which the said section may be cleaned, and the pipes X and X" are connected through the medium of a vertical pipe X', thus establishing communication between the lower end of the sections K through the 70 pipe O, section S, and pipes X", X', and X to the chimney. Situated in the pipe X, between the section K, to which it is connected, and the upper end of the vertical pipe X', is a damper N, by means of which direct draft 75 between the upper end of the sections K and the chimney is prevented or admitted, as may be desired.

In operation when the fire is started the damper is closed and the inner walls of the 80 chambers or flues E of the sections K are first heated and become of course warmer than the outer chambers or flues G, thus causing an upward current in the chambers E, as indicated by arrow, and a downward current 85 through the chambers or flues G, as also indicated by arrow. In turn the upward current in the chambers E draws the warm air from the upper chambers E, which passes down the said chambers G, warms the outer 90 surface or walls thereof, which are in contact with the air within the outer casing B, which is to be warmed, the air to be warmed thereby cooling off to some extent the walls of the flues or chambers G by giving its heat to the 95 air within the outer casing B, making the air within the flues G heavier, causing it to descend and to pass up through the flues or chambers E, thereby keeping up a constant circulation without the aid of the draft of the 100 chimney. The products of combustion pass out the lower end of the sections K into the

horizontal section S, through the pipes O, as indicated by arrow, and through the pipes X", X', and X to the chimney. It will be noted that the pipes O, which establish communication between the chimney and the said sections, afford a restricted outlet for the products of combustion.

From the above description it will be seen that I have produced a burner having a large heating-surface, thereby radiating the greatest possible amount of heat from a given amount of fuel, and which is so constructed that circulation will be maintained within the furnace without the aid of the draft of the chimney, which will be found to be a great saving in fuel and in the labor of feeding the same to the furnace.

The furnace may be constructed in various ways, depending upon the material of which it is composed. It may be made in vertical sections having an air-space through cross-section or whole, as shown in drawings, or it may be made in annular sections, one made on top of the other, with cup-joints for packing to make the space between the sections gas and air tight, and the sections may be of any desired number. For making a combination-furnace one or more sections may be used for hot water or steam, while the others are used for hot air, and the top of the fire-chamber A' is closed with a suitable trap J to separate the top of the fuel-chamber from the warm-air space or chamber, as will be readily understood.

35 The construction herein shown and described may be equally adapted to be used either as a gas or oil heating radiator for warming a room, with the advantage of a large heating-surface, the oil-heater taking the place of the grate within the fire-pot A', and the circulation will be through the several sections in the manner before described.

Having thus described my invention, what I claim, and desire to secure by Letters Patent, is—

45 1. A furnace consisting of a plurality of separate vertically-arranged chambers the inner walls of which constitute a fire pot or chamber, said chambers divided into two vertical flues having separate communications at their upper ends with the fire-pot and communicating with each other at their lower ends, substantially as described.

2. A furnace comprising a plurality of radially-arranged separate vertical sections the inner walls of which constitute a fire pot or chamber, the upper ends of the sections having openings in communication with the upper end of the fire-pot, and each section provided with a vertically-arranged partition having its upper end turned inward to constitute two separate flues in each chamber having separate communications with the upper end of the fire-pot, the lower end of the partitions being above the lower end of the sections forming a passage-way establishing

communication between the lower end of the two separate flues, and a communication between the sections and the chimney, substantially as described.

3. A furnace comprising a plurality of vertically and radially arranged sections, said sections being of a triangular truncated shape in cross-section and the truncated ends of the sections forming the walls of a fire-pot, the upper ends of the sections provided with an opening having communication with the upper end of the fire-pot, each section having a vertically-arranged partition with its upper end turned horizontally and dividing the openings in the sections into two separate passage-ways, and the lower ends of the partitions stopping at a point above the lower end of the sections constituting a passage-way forming communication between the lower ends of the flues formed by said partition, the lower end of the sections having a chimney communication, substantially as described.

4. A furnace comprising a plurality of vertical radially-arranged separate chambers, the inner walls of which constitute a fire-pot, the upper ends of the chambers having openings communicating with the upper end of the fire-pot, each chamber having a vertically-arranged partition dividing the sections into two separate flues, the lower ends of the partitions stopping at a point above the lower ends of the sections to form a communicating passage-way and the upper ends of the partitions turned inward to form separate passage-ways and communication respectively with the upper end of said flues, a horizontal section at the lower end of the said vertical sections, and communications between the lower ends of the vertical sections and the horizontal section, and the horizontal section provided with a chimney communication, substantially as described.

5. A furnace comprising a plurality of vertically and radially arranged separate sections, the inner walls of which constitute a fire pot or chamber, the upper ends of the sections having openings in communication with the upper end of the fire-pot, vertically-arranged partitions dividing the sections into separate vertical flues having communication with each other at their lower ends, and having separate communications at their upper ends with the upper end of the fire-pot, a pipe X having communication at one end with one of said vertical sections, a vertical pipe having communication with the said pipe X and also with the lower end of the vertical sections, and a damper situated in the pipe X between the upper end of the vertical pipe and the chamber, substantially as described.

6. A furnace comprising a fire pot or chamber, flues arranged therearound in pairs, the inner flue of each pair constituting the inner wall of the fire pot or chamber, the upper ends of the flues having separate communications with the fire-pot and the lower ends of the

flues communicating with each other, substantially as described.

7. A furnace comprising a fire-pot, flues vertically arranged therearound in pairs, one flue of each pair being adjacent the fire-pot and the other flue of each pair being removed therefrom, said flues having separate communications with the upper end of the fire pot or chamber, and the lower ends of the said flues having communication with each other, substantially as described.

8. A furnace comprising a fire pot or chamber, flues vertically arranged therearound in pairs, the inner flues of the said pairs being adjacent the fire-pot and the other flues of the pairs being removed therefrom, the upper ends of the said flues having separate communications with the upper end of the fire pot or chamber, the lower ends of the flues being in communication with each other, and a communication common to the lower

ends of the flues and the chimney, substantially as described.

9. A furnace comprising a plurality of radially-arranged separate vertical chambers 25 the inner walls of which constitute a fire pot or chamber, each chamber divided into two vertically - arranged flues having separate communications at their upper ends with the upper ends of the fire pot or chamber, the 30 lower ends of the flues being in communication with each other, and a comparatively-restricted communication between the lower ends of all of the flues and the chimney, substantially as described.

In testimony whereof I have hereunto set my hand in the presence of two subscribing witnesses.
